(57) **CLAIM**

The ornamental design for a woodworking gauge, as shown and described.

DESCRIPTION

FIG. 1 is a front, top, left side, isometric perspective view of a woodworking gauge in accordance with my design shown in a first position;

FIG. 2 is a front, bottom, right, isometric perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a front, top, left side, isometric perspective view of the woodworking gauge in accordance with my design shown in a second position;

FIG. 10 is a front, bottom, right, isometric perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a left side elevation view thereof; and,

FIG. 16 is a right side elevation view thereof.

The broken lines illustrate portions of the woodworking gauge which form no part of the claimed design.
